ELECTRON DISCHARGE DEVICE

Robert L. Norton, Santa Barbara, Calif., assignor to Penta Laboratories, Inc., Santa Barbara, Calif., a corporation of California

Application January 17, 1957, Serial No. 634,667

12 Claims. (Cl. 313—299)

This invention relates to an electron tube structure and more particularly to electrode configurations within electron discharge devices of the type arranged to form concentrated electron beams.

The principal object of this invention is to provide an electron tube having improved anode efficiency.

Another object of the invention is to provide an electron flow guide arrangement to extend the range wherein the plate current is relatively insensitive to plate voltage fluctuations so that a relatively large plate voltage swing will produce minimal plate current reduction under conditions of low plate voltages and therefore will result in greater plate efficiency.

It has been found in many conditions of use that an electron tube or discharge device will exhibit superior linear, distortion free characteristics when the flow of electrons from the cathode to the anode is guided or directed so as to fall upon the anode in substantially concentrated beams. A beam formed concentration of electrons at the anode, for example, improves the linearity in power amplifiers where the plate voltage swing is arranged to fall below the screen voltage.

A further object of this invention is to provide an improved electron flow guide or directing arrangement in an electron discharge device which provides a higher concentration of emitted electron flow toward certain preselected anode areas.

A feature of this invention is that with the improved electron flow guide or direction arrangement the linear operating ranges are greatly increased.

A more specific object of this invention is to provide an aligned grid electron tube or discharge device having one set of grids formed with elongate beam deflecting surfaces disposed in alignment with selected interposed grid members. This combination forms spaced electron beam guides that direct a highly concentrated flow of electrons outwardly from the cathode between two adjacent deflecting surfaces so the beam strikes the anode in a direct path of travel.

A still more specific object of this invention is to provide an electron beam control and directing arrangement to form and direct flow of a concentrated electron beam from cathode to anode by means of spaced pairs of electron deflecting members disposed adjacent the anode and formed to provide an electron deflecting surface substantially parallel to the direction of electron flow and of greater area than the leading face of the deflecting member adjacent the cathode.

It is an object of the invention to provide one group of each class of grid members aligned with the beam deflecting elements and a member or members of another group of each class of grid members disposed between selected members of the latter group.

Another feature of this invention is that the beam control elements are enabled to form the electron beam guide while at cathode potential whereat it is unnecessary to provide a separate power supply for the guide elements.

2

Because of this feature the guide elements may be connected directly to the tube's cathode internally of the tube without impairing materially the efficiency of tube operation.

5 Other objects of the present invention will become apparent upon reading the following specification and referring to the accompanying drawings in which similar characters of reference represent corresponding parts in each of the several views.

10 In the drawings:

Fig. 1 is a cut away perspective of a preferred embodiment of the invention.

Fig. 2 is a top plan sectional view of the embodiment of Fig. 1 taken at line 2—2.

15 Fig. 3 shows a graphic illustration of plate voltage and plate current and indicates the improved characteristics of a tube of this invention.

Fig. 4 is a diagrammatic view of the electrode structure of the invention showing the path of electron flow in relation thereto.

20 Fig. 5 is a fragmentary perspective of another embodiment of a beam deflecting electrode structure.

Fig. 6 is a fragmentary elevational view of another embodiment of the invention.

25 Referring now to the drawings and with particular reference to Figs. 1 and 2 there is provided a preferred embodiment of the invention in which an electron discharge device A is formed with an anode cup mounted on a tube base 16. The anode cup and tube base form a sealed envelope 17 which is evacuated to form the housing for the electrode elements of the tube. In this embodiment anode B functions in a dual capacity as the plate or anode electrode for the tube and also forms structural elements of the envelope 17.

30 It is to be understood, however, other conventional anode or plate structures could be used such as in arrangements where the entire anode is enclosed in an evacuated envelope. The tube A generally comprises a heater 18, a cathode, a control grid, a screen grid and a beam guide means indicated generally at C, D, E, and F, respectively.

35 The heater 18 is housed within the cylindrical cathode C and is arranged in a conventional manner to be connected to a filament power source so as to elevate the temperature of the cathode sufficiently to obtain electron emission therefrom.

40 The control grid D comprises a cage like structure which forms members 20 and 21 of control grid which in this embodiment takes the form of bars arranged in vertical equally spaced parallel alignment both in respect to each other and the cathode C.

45 The screen grid E comprises a similar but somewhat larger cage like structure formed with screen grid bars or members 22 and 23 also arranged in parallel equally spaced alignment with respect to each other and to the cathode C. The total number of control and screen grid bars is equal and bars 20 and 21 are radially aligned with bars 22 and 23 respectively and with cathode C.

50 The electron beam control means F comprises a cage structure which comprises parallel equally spaced metal ribbons 37 in parallel equally spaced alignment both with respect to each other and to the cathode. In this embodiment of the invention there is provided one ribbon 37 for each aligned pair of control and screen grid bars 20 and 22 respectively. Each pair of aligned bars 20 and 23 are aligned with a ribbon 37 and are designated as ribbon aligned bars, and the members or bars 21 and 23 between the ribbon aligned bars 20 and 22 are designated as intermediate grid bars.

55 In operation of the tube A, the anode B is provided with a relatively high positive voltage with respect to the cathode. The screen grid E is energized with a

60

positive potential somewhat lower than the plate potential. The control grid D is energized by a negative bias voltage upon which is superimposed a signal or driving voltage which varies the control grid potential. The precise bias voltage value of the control grid is largely dependent upon the class of operation in which the tube is to be employed. The beam directional means F may be arranged at cathode potential so in some tube designs the cathode C and ribbons 37 may be connected together interiorly of the tube A. In some instances the ribbons may be elevated slightly above cathode potential by a small positive voltage by connecting the ribbons to a separate terminal lead from source.

It has been found that tube A supplied with power as above specified will operate within an exceedingly wide range of plate voltage swing without substantial plate current drop in the region of low plate voltages.

Further, the range has been found to include the area wherein the screen voltage may be considerably above the plate voltage. The high screen voltage provides a high plate current without the necessity of driving the grid positive. Thus the tube is particularly satisfactory for utility in linear amplifiers such as radio frequency power amplifiers for incorporation in single side band transmissions.

Fig. 3 shows a plot wherein the plate voltage is indicated by the designation E_b and plate current at I_b . The chart shows an ordinary tetrode having unaligned grids plotted at 31. Curve 32 shows a conventional pentode tube having aligned grids. Curve 33 shows an equivalent tube made in accordance with this invention.

Curve 33 shows that greater plate current can flow with lower plate voltages than heretofore possible with suppressor grid tubes working under similar conditions. The electron flow of this tube structure is illustrated diagrammatically in Fig. 4. In Fig. 4 cathode C, control grid D, screen grid E and beam deflecting elements F are diagrammatically illustrated in a sectional plane encompassed within anode B. In Fig. 4 the number of intermediate control and screen grid bars 21 and 23 has been reduced to one for convenience of illustration. The addition of a plurality of intermediate grid bars as shown in Fig. 2 would produce a completely analogous flow pattern. In the diagram of Fig. 4, the calculated paths of travel of electrons from cathode C to anode B is generally indicated at 40.

Specifically, the relatively tangential paths of electron flow are indicated at T as opposed to the relatively radial paths R and the diagram illustrates that the electrons in paths T having large tangential components of velocity are deflected radially toward the anode and are thus not permitted to return to the screen.

It is understood that it is within the scope of the invention to include one or more intermediate grid bars 21 and 23 which are disposed between ribbon aligned grid bars 29 and 22. It is preferable that the number of a class of grid members or bars be an integral multiple of the total number of deflecting elements and that the members or bars in each class be equally spaced from one another.

The areas between adjacent electron guide ribbons 37, is, in effect, an electron gun in which a beam of highly concentrated electron flow is directed against the anode B. Electrons emitted from cathode C are arranged to pass from cathode between control grid bars 20 and 21 and are then propelled between screen grid bars 22 and 23. The screen grid E functions as an accelerating element to project electrons toward anode B. When the electrons are between the electron guide ribbons 37 there is a general repulsion affected by the guide element ribbons which tend to direct the electrons inwardly toward the mid-point between each two ribbons.

In prior art tubes employing suppressor grids there is a tendency for the suppressor grid to deflect some elec-

trons back to the screen grid. In the configuration of Fig. 4 the relatively wide or elongated guide surfaces 38 cause the electrons to be retained within the guide influence of the ribbons 37 until they reach a point where they are directly attracted by the positive anode more than by the screen even where the plate voltage is arranged to swing below the screen voltage. It can be seen that the general path of electron flow against the anode is directed radially toward the anode and reduces loss by reason of tangential approach. This reduces the likelihood of the electrons being collected by screen grid E before reaching the anode.

Two requirements are believed important to obtain the electron guide characteristic above specified. First, the aligned electron re-action surfaces 38 must be substantially longer than the surface 41 facing the cathode so the maximum electron deflection surface is immersed in the path of electron flow with both surfaces 38 substantially parallel with the desired path of electron flow.

The second requirement for the proper operation of each electron gun is that there be at least one intermediate control grid member disposed between the ribbon aligned grid members. The number of intermediate grid members and the relative spacing of the members with respect to relative distance between cathode and anode is dependent upon various operational requirements, and also the intended voltage ranges within which the tube is designed to be operated.

In Figs. 1 and 2 guide elements F have been indicated as comprising ribbons 37. In effect, the side surfaces 38 of each ribbon 37 forms a radially aligned elongate electron guide. It is contemplated within the scope of invention that other equivalent means of constructing such a radially elongate guide could also be employed satisfactorily. For example, referring to Fig. 5, each ribbon 37 could be replaced with three spaced vertically aligned wires 45 supplied with the same voltage as the ribbons 37. Such a device would operate to provide the elongated deflecting surface and would function in substantially the same manner as ribbons 37.

In the embodiment of the invention shown in Figs. 1 and 2 the grid members 21 have been generally indicated as parallel with respect to the cathode. It is also contemplated to be within the scope of the invention that the electron gun could be oriented horizontally in a tube structure such as indicated in Fig. 6. In Fig. 6 a tube G is provided with two parallel control grid wires 46^a and 46^b formed in spaced helices circumscribing the cathode 47. A set of screen grid wires 48^a and 48^b are arranged in interposed helices circumscribing the cathode exteriorly of the control grid wires 46^a and 46^b and with the screen grid wire 48^a aligned with the control grid wire 46^a and with the screen grid wire 48^b aligned with control grid wire 46^b. A beam deflecting element comprising a ribbon member 49 is formed in a helix circumscribing screen grid wire 48^a and with the surface 50 of ribbon 49 aligned to face cathode 47 so that the two flats 51 of the ribbon provide electron re-action or guide surfaces aligned with two wires 46^a and 48^a. Guide wires 46^b and 48^b form the intermediate grids. The elements of the grids and guides of the electron gun are thus formed by adjacent turns of the helix formed by wires 46^a and 48^a and ribbons 49. In this tube embodiment there will be a stream or beam of electrons directed against anode 55 of tube G formed by an electron gun between adjacent turns or folds of the helices. The helical electron beam will be disposed in the gap formed by adjacent turns of ribbon 49. Tube G thus functions in substantially the same manner as described in Figs. 1 and 2 and illustrated in Figs. 3 and 4 except that the electron beam is directed in a helical pattern rather than the vertical pattern as before described.

Although the foregoing invention has been described in some detail by way of illustration and example for purposes of clarity of understanding, it is understood

that certain changes and modifications may be practiced within the spirit of the invention as limited only by the scope of the appended claims.

What is claimed:

1. An electron discharge device having a cathode and an anode and a control grid comprising means to channel electron discharge flow through a selected path from cathode to anode, said means comprising electron deflector elements aligned with selected spaced grid members but not with others and immersed in the flow path of electrons from cathode to anode, said elements being elongate in the direction of electron flow.

2. An electron discharge device having a cathode and an anode and a control grid comprising spaced means to form a channel of concentrated electron flow through a selected path from cathode to anode with minimal divergence and maximum suppression of secondary emission, said spaced means comprising electron deflector elements aligned with selected spaced grid members and arranged to straddle other of said grid members, said deflector elements immersed in the path of flow of electrons from cathode to anode.

3. In an electron discharge device of the type having a cathode to emit electrons and an anode to receive electrons, the combination of first and second control grid means disposed between the cathode and anode and electron beam deflecting means disposed between said grid means and said anode, said deflecting means having two oppositely facing elongate electron reaction surfaces between the anode and cathode and aligned with said first grid means with said first and second control grid means each being substantially equidistantly spaced from said cathode, and said second control grid means disposed between said first grid means.

4. A device according to claim 3 and wherein each said element of said deflecting means comprises a plurality of aligned wires.

5. A device according to claim 3 and wherein each element of said deflecting means comprises a conductive ribbon.

6. A device according to claim 3 and wherein said first and second grid means each comprises a length of wire formed in a helix around the cathode and the members of said first grid means comprising adjacent turns of the helix and wherein said electron beam deflecting means comprises a length of ribbon arranged in a helix formed around the first grid means.

7. In an electron discharge device of the type having a cathode to emit electrons and an anode to receive electrons, the combination of first and second control grid means located between the cathode and anode, first and second screen grid means disposed between said control grid means and said anode, electron beam deflecting means arranged between said screen grid means and said anode, each said first control grid means, first screen grid means, and electron beam deflecting means having a pair of members disposed in spaced aligned relation, each member of said deflecting means having two oppositely facing elongated electron reaction surfaces extending between the anode and cathode aligned with a respective member of said first control grid means and said first screen grid means, said first and second control grid means being substantially equidistantly spaced from said cathode, said second control grid means having at least one member disposed between two members of the first control grid means, said first and second screen grid means being substantially equidistantly spaced from said cathode, and said second screen grid means having at least one member flanked by two members of said first screen grid means aligned with a member of said first control grid means.

8. In an electron discharge device of the type having a cathode to emit electrons and an anode to receive electrons, the combination of control grid means disposed between the cathode and anode arranged to control the

flow of electrons therebetween, electron beam deflecting means between said control grid means and said anode to deflect electron flow to channel a concentrated electron beam directed toward the anode, said deflecting means comprising a plurality of elements each having two oppositely facing elongate electron reaction surfaces extending between the anode and cathode to guide electron flow adjacent thereto in a path generally parallel to said surfaces, said control grid having a plurality of spaced apart members with one said member aligned with each deflecting means element and at least one said grid member positioned and arranged between adjacent deflecting element aligned grid members.

9. In an electron discharge device of the type having a cathode to emit electrons and an anode to receive electrons, the combination of a plurality of parallel, staggered, spaced first and second control grid members arranged to circumscribe the cathode, a plurality of electron beam deflecting members disposed between said grid members and the anode, each said deflecting member disposed parallel to and aligned with one said first grid member, said deflecting member in cross-section formed with two elongate faces and at least one smaller face, said small face facing said cathode and said elongate faces arranged in alignment with a first grid member and cathode in position so that both faces are immersed in the electron stream flow from the respective sides of the aligned first grid member, and at least one said second control grid member arranged between each two first control grid members and spaced substantially equidistantly therewith from said cathode.

10. The combination according to claim 9 and wherein there is provided first screen grid members aligned between each first control grid member and aligned deflecting member, and at least one second screen grid member disposed between each first screen grid member and spaced substantially equidistantly from said cathode in alignment with a second control grid member.

11. In an electron discharge device of the type having a columnar cathode to emit electrons and a cylindrical anode circumscribing the cathode to receive electrons, the combination of a plurality of parallel, staggered, equidistantly spaced first and second control grid members arranged to circumscribe the cathode between the cathode and anode and spaced equidistantly from said cathode; a plurality of parallel, staggered, equidistantly spaced first and second screen grid members arranged to circumscribe the cathode between the control grid members and the anode and each spaced substantially equidistantly from said cathode; each said first screen grid member arranged in alignment with a first control grid member and each said second screen grid member arranged in alignment with a second control grid member; a plurality of electron beam deflecting members disposed between said grid members and the anode; each said deflecting member disposed parallel to and aligned with one aligned pair of first screen and control grid members; and each said deflecting member formed with two oppositely facing elongate electron beam reaction surfaces disposed between the cathode and anode and aligned with respectively aligned grid members, and a substantially smaller electron beam reacting surface facing the cathode.

12. In an electron discharge device of the type having a columnar cathode to emit electrons and an anode to receive electrons circumscribing the cathode, the combination of: a first control grid member arranged in a helix circumscribing the cathode; a second control grid member arranged in a helix interposed between turns of the helix formed by said first control grid member; said first and second control grid members equidistantly spaced from said cathode; a first screen grid member formed in a helix circumscribing and aligned with said first control grid member; a second screen grid member formed in a helix interposed between said first screen grid member and circumscribing said second control grid member and

aligned therewith; said first and second screen grid members spaced equidistantly from said cathode; an electron beam deflecting member arranged in a helix circumscribing said first screen grid member and aligned therewith; said electron beam deflecting member formed with two oppositely facing electron beam reacting surfaces extending between the cathode and anode in alignment with the first screen grid member and first control grid member; and a substantially smaller electron beam reaction surface facing the cathode.
